METALLIC FLAME RADIATION

Carl Kenty, Cleveland Heights, Ohio, assignor to General Electric Company, a corporation of New York

Application September 3, 1953, Serial No. 378,242

7 Claims. (Cl. 313—185)

This invention relates in general to the production of radiation by the excitation of metallic spectra. More particularly, it relates to the production of light by the use of active nitrogen to excite metal vapors to spectral emission.

An object of my invention is to provide a novel light source.

Another object of my invention is to provide a new and improved means for exciting metallic spectra.

In accordance with my invention, I have discovered that under certain conditions the metallic spectra of the electrodes of discharge devices may be excited to produce "flames" of appreciable luminosity. The excitation occurs when short high current discharges are caused to flow between the electrodes in an envelope containing a gaseous filling comprising an inert gas at a pressure in excess of one centimeter of mercury and a small percentage of nitrogen. The electrodes are unactivated and preferably maintained cold to assure copious sputtering of the electrode metal. Thus, when a discharge occurs, the electrodes are surrounded with metal vapor whereof the atoms are excited to spectral emission by the active nitrogen simultaneously produced by the discharge.

Further objects and advantages of my invention will appear from the following description taken in conjunction with the accompanying drawing. The features of my invention believed to be novel will be more particularly pointed out in the appended claims.

In the drawing:

Fig. 1 is a schematic illustration of an electric discharge device and operating circuit therefor for the production of metallic spectra in accordance with my invention.

Fig. 2 is a longitudinal sectional view through an electric discharge device for the production of metallic flame spectra and embodying my invention.

The metallic spectra or flames produced in accordance with my invention appear to be excited by the active nitrogen produced by the discharge. Active nitrogen as such has been known for many years. An admirable account of its physical and chemical properties, and its history, is given in "Active Nitrogen—A New Theory" by S. K. Mitra, 1945, published by the Indian Association for the Cultivation of Science, Calcutta, India. If a condensed spark, that is an oscillatory discharge, is passed through nitrogen at a pressure of the order of one millimeter, a yellow afterglow will be observed. This yellow glow consists of a selection of the so-called first positive bands of nitrogen.

Many theories have been advanced to explain active nitrogen, an account of some of which is given by S. K. Mitra above. According to one theory first suggested by A. G. Gaydon and further elaborated by R. W. Nicholls in the Journal of Chemistry and Physics, 20, 1040 (1952), active nitrogen is a mixture of three and possibly four kinds of metastable nitrogen (N_2) molecules. These molecules have a long life. One of them with the aid of a collision of another body, a free elec-

tron according to Nicholls, is converted into another kind of excited state of nearly the same energy, which radiates the familiar yellow and red bands of active nitrogen. This reaction takes place very slowly and so the afterglow has a long life.

I believe that some or all of these metastable nitrogen molecules cause the excitation of the metal atoms to produce the "flames" above mentioned. However, in order to produce flames of appreciable intensity and luminosity, certain conditions must be observed. Referring to Fig. 1, a suitable apparatus for achieving the conditions in accordance with my invention is diagrammatically illustrated. The discharge device comprises a vitreous envelope 1 into which is sealed a pair of electrodes 2, 3 in the form of metal spheres mounted on the ends of lead wires 4, 5 and defining a short arc gap. The spherical electrodes 2, 3 are unactivated and will consist of the metal whereof the spectral emission is desired, for instance tungsten productive of a blue flame.

To produce a good flame, that is one of high luminosity, the gas pressure and composition must be properly selected in accordance with my invention and also the electric discharge must have the proper characteristics. Since the flame is produced by the excitation of the sputtered metal from the electrodes, it is desirable to have copious sputtering. I have found that a favorable gas mixture for the flames must comprise in excess of 3 centimeters of mercury of an inert gas with a small percentage of nitrogen. For instance, a suitable gas mixture may consist of argon at a pressure of 10 to 50 centimeters of mercury, with 1 to 3 per cent of nitrogen added. These quantities are not critical, but at a pressure below 10 centimeters of mercury the degree of electrode sputtering decreases, and below 3 centimeters the amount of sputtering is too low to produce a flame of appreciable luminosity.

The spacing of the metal electrodes 2, 3 is not critical. However, since the sputtering of the electrode metal is the effect sought, it will be appreciated that a long arc gap is unnecessary and merely increases the voltage required to produce the discharge. I have found that an arc gap less than 1 centimeter in length, for instance a spacing of 1 to 4 millimeters between the spherical electrodes 2 and 3, is suitable for the purpose of the invention.

For high luminosity of the metallic spectra, the discharge must consist of short pulses of current of high intensity. It has not as yet been determined whether a discharge of this nature is desirable because it produces a greater degree of electrode sputtering or because it is more efficient in producing active nitrogen. Probably it is desirable on account of both reasons. In any case, my experiments have clearly demonstrated that the quantity of light produced when a given quantity of electrical energy is discharged through the tube in the form of short high intensity pulses, is many times greater than when the same quantity of energy is discharged through the tube as a uniform low intensity current.

The most favorable type of discharge which I have found is a condensed spark or damped oscillatory discharge. Referring to Fig. 1, such a discharge is produced by means of a high voltage transformer 6 comprising a primary winding 7 connected to a variable autotransformer 8, which is in turn energized from the usual 115 to 120 volt, 60-cycle commercial alternating current supply. The secondary winding 9 of transformer 6 may provide a maximum open circuit voltage of 10,000 volts and a short circuit current of 30 milliamperes. There is a common neon sign transformer which meets the above-stated requirements for transformer 6. The secondary winding 9 of the transformer is connected in series with

an external air gap 11 across electrodes 2, 3 of discharge device 1. A capacitor 12 which may have a rating of approximately 500 micromicrofarads is shunted across secondary winding 9. The external air gap 11 preferably should have electrodes of silver or tungsten to prevent excessive wearing away. I have found that for a given air gap length, the transformer voltage should be adjusted (by sliding the autotransformer tap) to as low a value as possible while yet avoiding failure to spark. A sort of hissing noise emanates from air gap 11 under these circumstances.

The most copious sputtering and the most luminous flames are obtained when the electrodes are cold. Since continual sparking will cause heating of the electrodes, sometimes to redness, it is advantageous to use the spark intermittently. It will be appreciated, of course, that this may be done by using a rotating switch or other equivalent device, if so desired. Furthermore, the heat dissipating capacity of the electrodes may be increased by any one of the methods well-known in the art, for instance by use of heavier lead-in wires and radiating fins.

In order to obtain the pure spectrum of the electrode metal, it is necessary to have a very good exhaust of the bulb previous to the filling with the argon and nitrogen mixture. Otherwise, it will be found that the flames are colored violet by the cyanogen (CN) bands. Preferably, the exhaust should include a high temperature baking, for instance to 450° C. for one hour. Then the electrodes should be heated to bright redness in oxygen at 5 to 10 millimeters pressure in order to remove entirely all carbon and carbonaceous gases yielding cyanogen. Glow discharge heating is satisfactory for this purpose. Further heating of the electrodes in hydrogen at 5 to 10 millimeters pressure reduces the oxide and a final heating in argon drives out absorbed hydrogen.

When the switch 10 is closed to energize transformer 6, the discharge occurring through the device 1 is of the type generally known as a condensed spark discharge. A series of sparks occurs across the air gap 11, and each spark is in the nature of a damped high frequency oscillation. With the circuit constants that have been stated, the oscillatory frequency is in the range of 10 megacycles per second. The discharge is highly damped, and thus the current flow through the device 1 is in the nature of a continuous series of short high intensity pulses. It will be appreciated that a discharge of this character causes considerable radio and television interference. To minimize such interference, the tube 1 should preferably be operated inside a grounded metal screen enclosure, and the air gap 11 along with the circuit apparatus should also preferably be so enclosed.

The flames which are produced by the discharge have been indicated within the tube 1 insofar as drawing limitations will permit. In the arc gap space immediately between the spherical electrodes 2, 3, there occurs a bright spark 14 of high intensity which shows the arc spectrum lines of argon and nitrogen and also the spectral lines of the electrode metal. Surrounding the electrodes, there is a bright luminous cloud 15 which looks remarkably like a flame and which contains the spectral lines of the electrode metal. Surrounding the bright cloud or flame 15, there is luminous region of much lesser intensity indicated at 16 which shows the yellow and red bands of active nitrogen.

The color and appearance of the bright cloud or flame 15 will depend upon the metal selected for the electrodes 2, 3. I have produced the flames of many different metals. Some of the outstanding ones are: tungsten, giving a blue flame; vanadium, red; columbium, yellow; palladium, green; chromium, blue-violet, and iron, violet.

Of the various metals which I have tried, columbium gives the highest luminosity. I have estimated the light producing efficiency of such a device with columbium electrodes to be of the order of one lumen per watt. For the production of spectacular lighting effects or for

the production of metallic spectra, the present discharge device is a highly effective source. The flame spectrum consists of the line spectra of the metal atoms of the electrodes. However, the spectral lines in the flames have a somewhat different intensity distribution as compared to those obtained in an ordinary arc between the given metal electrodes in air.

Referring to Fig. 2, there is illustrated a discharge device embodying the invention wherein a plurality of electrode gaps are mounted in series within a single envelope. The device comprises a tubular vitreous envelope 21 having stems 22 and 23 at opposite ends through which are sealed a pair of terminal electrodes 24, 25. In between the ends of the electrodes 24 and 25 are supported a plurality of spaced intermediate electrodes 26 which, together with the end electrodes 24, 25, form a series of arc gaps 27 distributed across the length of the tube. The intermediate electrodes 26 are supported in place by short support wires 28 which are preferably spot-welded to the electrodes near their midpoint; the lower ends of the support wires are embedded in a glass support rod 29. The rod 29 may be held in place within the tube by means of auxiliary support wires 31 embedded into the stem presses 22, 23 at the ends of the tube 21.

When the discharge device of Fig. 2 is energized in an electrical circuit similar to that illustrated in Fig. 1, a bright flame of the electrode metal spectrum forms about each arc gap 27. If the end electrodes 24, 25 and also the intermediate electrodes 26 are all of the same metal, the flames about each gap will all be of the same nature. If desired, the portions of the electrodes adjacent the various gaps may be made of different metals and then a number of vari-colored flames may be obtained within a single envelope and the results are very pretty.

Whereas in the specific embodiments of the invention which I have described, I have stated the inert gas to be argon, the other inert gases may likewise be used. Helium and neon give flames about as bright as that obtained with argon and of identical spectral quality.

Krypton gives a flame fully as bright, but of different spectral quality. Xenon, however, gives a relatively weak flame of considerably different spectral quality.

When xenon is used as a rare gas, I have observed a rather surprising result which is not present with any of the other rare gases. With xenon, the yellow afterglow of active nitrogen is not obtained under any circumstances. This would appear to indicate that the metastable nitrogen state, mentioned earlier as the exciter of the yellow active nitrogen bands, is losing its energy to the xenon atoms and exciting them instead of the nitrogen. In one experiment wherein I used a gaseous filling consisting of argon at 20 centimeters of mercury, xenon at 3 centimeters, and nitrogen at 1 centimeter, there was very little yellow afterglow of active nitrogen, but a mild after-fluorescence of the glass. Such a fluorescence of the glass is not observed in any of the other cases, and I believe that it is due to the resonance radiation of xenon as excited by the nitrogen metastable molecule in question.

The above-described property of xenon may be made use of to eliminate, when desired, the yellow glow and afterglow which surrounds the metallic spectrum flame in the devices of Figs. 1 and 2. The yellow glow sometimes detracts from the beauty of the flame, and by adding some xenon to the argon and nitrogen mixture, the yellow glow can be entirely suppressed without apparently diminishing the intensity of the flame itself. A suitable gas filling for this purpose may consist of argon at 20 centimeters of mercury, xenon at 3 centimeters, and nitrogen at 1 centimeter.

While certain specific embodiment of the invention have been shown and described, various modifications and other applications of the invention will readily occur to those skilled in the art. The appended claims are therefore intended to cover any such modifications coming within the true spirit and scope of the invention.

What I claim as new and desire to secure by Letters Patent of the United States is:

1. An electric discharge device comprising a vitreous envelope having sealed therein a pair of terminal electrodes of unactivated metal, a plurality of intermediate unactivated metal electrodes insulatively mounted within said envelope and spaced end-to-end between said terminal electrodes and with short arc gaps between adjoining electrodes, and a gaseous filling within said envelope comprising an inert gas at a pressure in excess of 3 centimeters of mercury and a small percentage of nitrogen.

2. An electric discharge device comprising an envelope having sealed therein a pair of unactivated metal electrodes defining an arc gap, and a gaseous filling within said envelope comprising an inert gas at a pressure in excess of 3 centimeters of mercury and a small percentage of nitrogen.

3. An electric discharge device comprising a vitreous envelope having sealed therein a pair of unactivated metal electrodes defining an arc gap, and a gaseous filling within said envelope comprising an inert gas at a pressure in the range of 10 to 50 centimeters of mercury and including 1 to 3 per cent of nitrogen.

4. An electric discharge device comprising a vitreous envelope having sealed therein a pair of unactivated metal electrodes defining an arc gap, and a gaseous filling within said envelope comprising argon at a pressure in the range of 10 to 50 centimeters of mercury and including 1 to 3 per cent of nitrogen.

5. An electric discharge device comprising a vitreous envelope having sealed therein a pair of unactivated metal electrodes defining an arc gap, and a gaseous filling within said envelope comprising argon at 20 centimeters pressure, xenon at 3 centimeters pressure and nitrogen at 1 centimeter pressure.

6. An electric discharge device comprising a vitreous envelope having sealed therein a pair of terminal electrodes of unactivated metal, a plurality of intermediate unactivated metal electrodes insulatively mounted within said envelope and spaced end-to-end between said terminal electrodes and with short arc gaps between adjoining electrodes, and a gaseous filling within said envelope comprising an inert gas at a pressure in the range of 10 to 50 centimeters of mercury and including 1 to 3 per cent of nitrogen.

7. An electric discharge device comprising a vitreous envelope having sealed therein a pair of terminal electrodes of unactivated metal, a plurality of intermediate unactivated metal electrodes insulatively mounted within said envelope and spaced end-to-end between said terminal electrodes and with short arc gaps between adjoining electrodes, and a gaseous filling within said envelope comprising argon at 20 centimeters pressure, xenon at 3 centimeters pressure and nitrogen at 1 centimeter pressure.
